[57] CLAIM

The ornamental design for a telephone station set, as shown and described.

DESCRIPTION

FIG. 1 is a front, top and right side perspective view of a telephone station set showing our new design;
FIG. 2 is front elevational view thereof;
FIG. 3 is a top plan view thereof;
FIG. 4 is a bottom plan view thereof;
FIG. 5 is a left side elevational view thereof;
FIG. 6 is a right side elevational view thereof;
FIG. 7 is a rear elevational view thereof; and
FIG. 8 is a front, top and right side perspective view of the stand generally similar to FIG. 1, but with the display panel in tilted position, and with the handset inverted upon its support.

FIG. 1

FIG. 2

FIG. 3

FIG. 4

FIG. 5

FIG. 6

FIG. 7

FIG. 8
